FIG. 4.

FIG. 2.

UNITED STATES PATENT OFFICE.

ROBERT NIEDERGESAESS, OF SEATTLE, WASHINGTON, ASSIGNOR TO AMERICAN SMOKE-LESS BURNER COMPANY, A CORPORATION OF WASHINGTON.

FURNACE.

1,185,526.

Specification of Letters Patent. Patented May 30, 1916.

Application filed December 17, 1914. Serial No. 877,679.

To all whom it may concern:

Be it known that I, ROBERT NIEDERGESAESS, a citizen of the United States, residing at Seattle, in the county of King and State of Washington, have invented certain new and useful Improvements in Furnaces, of which the following is a specification.

This invention relates to mechanically operated stokers for furnaces and is in the nature of improvements to the invention for which I filed a patent application January 15, 1914, bearing Serial No. 812,254.

The object of my improvements is the perfecting of apparatus of this character to render the same more efficient in operation, which will afford a uniform fuel feed and cause the same to be consumed with little waste.

The invention consists in the novel construction, adaptation and combination of parts, as will be hereinafter described and claimed.

In the accompanying drawings, Figure 1 is a longitudinal vertical section of apparatus embodying the present invention. Fig. 2 is a plan view of the same, but with the fender plates disposed in different positions from which they are illustrated in Fig. 1. Fig. 3 is a view shown partly in end elevation and partly in vertical transverse section of the mechanism for supplying fuel to the fuel receptacle of the furnace. Fig. 4 is a horizontal section taken substantially through 4—4 of Fig. 1.

The reference numeral 5 designates a table which is supported on posts 6 and may constitute the base of a furnace. Depending from said table and rigidly secured thereto, as by bolts 7, is a fuel receptacle 8 of substantially the shape of an inverted frustum of a cone. Disposed axially of said receptacle and extending upwardly from the floor 9 thereof is a tubular column 10 provided exteriorly with a helical rib 11 similar to the thread of a screw. Extending down into the receptacle 8 is the casing 12 of a fire-pot which is lined with fire-brick 13 or an equivalent. This fire-pot is of a funnel-shape having an upper flaring portion 14 and a throat 15 therebelow of a substantially cylindrical form with a diameter somewhat greater than the diameter of the outside of the rib 11 of the column which extends through said throat. Said

fire-pot is provided with an external flange 55 or track element 16 which is mounted upon rollers or wheels 17 journaled upon axles 18 supported in suitable boxes provided in the peripheral wall of the receptacle 8. Externally of the fire-pot casing 12 is a helical 60 flange or screw-blade 19. Ridges 20 and 21 respectively project inwardly from the walls of the receptacle 8 and the throat 15 and are inclined from vertical planes extending radially of the axes of the receptacle and 65 throat.

22 represents a pipe whereby water is supplied to the receptacle to approximately the level indicated by W L in Fig. 1. Provided on the fire-pot casing are peripheral gear-teeth 23 which mesh with a spur-gear 24 mounted on an upright shaft 25 which is rotated by gears 26 from an upright shaft 27. The latter, in turn, is rotated by bevel gears 28 from a horizontal shaft 29 which 75 is driven from a motor 30 by a belt 31 passing about pulleys 32 and 33 on the shaft 29 and the armature shaft of the motor.

34 represents a rotary fan or blower which is driven from the motor 30 by a belt 80 35 to force air for combustion purposes through the conduit 36 provided within the column 10. Rigidly secured to the upper end of said column is a twyer head 37 having a plurality of perforated radially directed horns 38 and 38¹ through which the air blast is delivered in a number of jets to the fire. Said horns are formed with upper and lower surfaces 39 and 39¹ which are sloped circumferentially to afford a 90 screw-like structure which tends to cause the revolving fuel engaging the same to be forced upwardly. One of the horns, 38¹, extends as shown in Fig. 1, above the other horns and serves to disrupt or break masses 95 of coke or clinkers which may impinge the horn.

The perforations 40 of the various horns are disposed at the sides of the latter in the direction in which the fuel is revolved so 100 that there is no danger of their becoming choked by fuel being forced thereinto.

In the operation of the apparatus, the solid combustion products thereof are forced upwardly from the fire-pot onto the rim of the latter, and in their revoluble travel they encounter a horizontally disposed plate 41 having an inclined guiding face 41¹ (Fig. 2)

which serves to return the relatively small lumps into the fire-pot while the large pieces or clinkers pass above the plate to be directed by an inclined wall 42 from the top 5 of the fire-pot onto and over the table 5.

Included in the invention is a conveyer for feeding the fuel to the receptacle 8. Said conveyer consists of a chain belt 43 operating in a trough 44 leading from a 10 coal hopper 45 into said receptacle, as best shown in Fig. 3. The chain 43 passes about an idler 46 and a sprocket-wheel 47 which is mounted upon a shaft 48. This shaft is intermittently rotated by having a ratchet 15 wheel 49 thereon engaged by a spring-pressed pawl 50 which is carried by a vibratory arm 51 loosely mounted on the shaft 48. The arm 51 is actuated by a pitman 52 from a pin 53 of a crank shaft 54 which is rotated 20 by means of a belt 55 from the shaft 29. The conveyer chain 43, as shown in Fig. 3, passes into the receptacle 8 to deposit the coal therein and, to prevent any lumps reaching the sprocket wheel 47, the chain 25 is caused to pass through a slot 56 of a bracket-piece 56¹.

Subjacent to the fire-pot and rotatable therewith is a plurality of curved blades 57, Figs. 1 and 4, which serve to impart revolute motion to the coal and transmit the same centripetally to the thread 11.

In operation, the fire-pot is continuously rotated while the receptacle 8, the screw column 10 and the twyer head 37 are 35 movable. The fuel in the nature of coal is fed into the receptacle by means of the conveyer chain 43. The fuel thus deposited within the receptacle falls into the water contained in the receptacle, and is forced 40 down by the revolving screw-thread 19 acting in coöperation with the ribs 20 which tend to prevent any turning of the coal until it is brought within the scope of scoop-blades 57. When this occurs, the revolving 45 blades 57 impart corresponding motion to the coal and cause it to progressively travel to the stationary column 10. The revolute movement of the coal when it encounters the screw-thread 11 of said column causes it 50 to be thereby raised through the throat 15 into the upper portion 14 of the fire-pot. In such ascending movement of the coal, it is given a rotary movement which is afforded by the revolving ribs 21 and by contacting 55 with the inner periphery of the fire-pot. As the coal is thus turned, it is subject to the heat due to the burning at or near the top of the pot, and becomes more or less coked, which is principally broken up by being impinged against the horns of the twyer head. Lumps of coke which may overflow the fire-pot are pushed back into the latter by the inclined face 41¹ of plate 41 and the ashes 60 in the form of clinkers, upon engaging the plate 42, are directed thereby over the top

of the table 5. The fire is sealed with respect to the admission of air accompanying the coal into the fire-pot by the water with which the bottom of the receptacle is flooded. The air for combustion purposes is 70 driven by the blower 34 through the conduit 36 to be discharged through the perforations 40 provided in the various horns of the twyer head, thus distributing the air to mingle with the combustible gases emanating from the fuel to be consumed at the top of the fire-pot. According to the present invention, the conveyer chain 43 is operated at a speed to supply coal sufficient to meet the demand, and through the offices of the 80 stationary and rotary screw-devices and the revolving scoop-blades the fuel is elevated to be burnt in the fire-pot.

What I claim as my invention, is—

1. In a device of the class described, a fuel 85 receptacle, a rotary fire-pot having an open bottom, and fixed means coacting with said rotary fire pot for progressively elevating fuel from said receptacle into said fire pot.

2. In a device of the class described, a fuel 90 receptacle, a rotary fire-pot, and screw devices extending from the receptacle and affected by the rotation of said fire-pot to elevate fuel into the latter from said receptacle.

3. In a device of the class described, a fuel receptacle adapted to hold water to a predetermined depth, an annular fire pot positioned within the receptacle, means to rotate said fire pot, and non-movable means co-acting with said rotatable fire pot to elevate fuel into the space within said fire pot.

4. In a device of the class described, a fuel receptacle, an annular fire-pot extending into said receptacle, means to rotate said fire-pot about a vertical axis, said receptacle being supplied with water to submerge the lower end of the fire-pot, means rotatable with the fire-pot for moving the fuel centripetally of the receptacle and below the fire-pot, and means extending into the fire-pot for elevating the fuel received from the aforesaid means up into the fire-pot.

5. In a device of the class described, a fuel receptacle, an annular fire-pot disposed to 115 rotate about the vertical axis of said receptacle, a tubular column provided with an external screw and extending from the receptacle into said fire-pot, means provided in the fire-pot and coöperating with said column 120 for elevating fuel into said fire-pot from the receptacle, and means for supplying air for combustion purposes through said column.

6. In apparatus of the class described, the combination of a fuel receptacle, a screw-threaded column extending upwardly from the bottom thereof, means to supply fuel to said receptacle, a fire-pot mounted for rotary movements about the axis of said column, means carried by said fire-pot for impelling 125

the fuel into position to be elevated by said column, and means to supply air for combustion purposes through the column.

7. In apparatus of the class described, a 5 rotary fire-pot, means actuated by the rotation of the fire-pot for progressively elevating fuel into the fire-pot and eventually causing the residue of the consumed fuel to be discharged upon the top of the fire-pot, and 10 means rendered effective by the rotation of the fire-pot for effecting the removal of such discharged residue from the top of the fire-pot.

8. In apparatus of the class described, an 15 annular rotary fire-pot, means for elevating fuel into the fire-pot to be burned and delivering the resultant ashes upon the top of the fire-pot, a relatively thin deflector inclined with respect to the radii of the fire-pot for 20 returning into the latter unconsumed portions of the fuel which may be delivered upon the top of the fire-pot with the ashes, and means for moving the ashes away from the fire-pot.

25 9. In apparatus of the class described, a fuel receptacle, means for effecting the movement of fuel from the peripheral wall of said receptacle toward the center thereof, a rotary annular fire-pot, screw devices 30 operating with the fire-pot for elevating the fuel in the fire-pot, a tubular member extending axially into the fire-pot, a twyer-head provided for said member, and means for supplying air under pressure to the 35 twyer head through said member.

10. In apparatus of the class described, a fuel receptacle, means for effecting the movements of fuel from the peripheral wall of said receptacle toward the center thereof, 40 a rotary annular fire-pot, screw devices operating with the fire-pot for elevating the fuel in the fire-pot, a tubular member extending axially into the fire-pot, a twyer-head formed with a radially directed perfor- 45 rated horn fixedly secured to said member.

11. In apparatus of the class described, a fuel receptacle, means for effecting the movement of fuel from the peripheral wall of said receptacle toward the center thereof, a 50 rotary annular fire-pot, screw devices operating with the fire-pot for elevating the fuel in the fire-pot, a tubular member extending axially into the fire-pot, means for supplying air under pressure through said 55 member into the fire-pot, and means secured to said member for breaking the coke or clinkers when the same are revolubly moved into contact therewith by the turning of the fire-pot.

60 12. A device of the class described, comprising a fuel receptacle, a rotary fire-pot having an opening in its bottom, a stationary screw coacting with said fire-pot to elevate fuel into the latter, and a twyer-head se- 65 cured to the top of said stationary screw.

13. A device of the class described, comprising a fuel receptacle, a rotary fire-pot disposed within said fuel receptacle, a stationary screw coacting with said rotary fire-pot for elevating fuel into the latter, said 70 stationary screw being provided with an air passageway, and a twyer-head secured to the top of said screw and connected with said passageway, said twyer head being provided with radially directed perforated 75 horns for breaking coke or clinkers when the same are moved into contact therewith by the rotation of said fire-pot.

14. A device of the class described, comprising a rotary fire-pot having an axially 80 disposed stationary screw to coact with said fire pot and elevate fuel thereinto, a twyer-head on said screw, said twyer-head being provided with a radially projecting horn adapted to engage with moving masses of 85 fuel to break up such moving masses.

15. A device of the class described, comprising a rotary fire-pot having an axially disposed stationary screw adapted to coact 90 with said fire-pot to convey fuel thereinto.

16. A device of the class described, comprising a fuel receptacle, a rotatable fire-pot disposed therein, scoop-blades rotatable with said fire-pot to move fuel toward the center of said fuel receptacle, and a stationary 95 screw coacting with said scoop blades and said rotary fire-pot to convey fuel into said fire-pot.

17. In apparatus of the class described, a fuel receptacle, means for effecting the movement of the fuel from the peripheral wall of said receptacle toward the center thereof, a rotary fire-pot and stationary screw devices coacting with the rotatory movements 100 of said fire-pot for elevating the fuel in the 105 fire-pot.

18. An underfeed furnace comprising a furnace chamber, a rotative firepot therein, means to conduct air to the firepot, a fixed upstanding centrally arranged spiral ledge 110 extending upwardly through the firepot, and means to deliver fuel to the chamber and force it inwardly in a compact mass against said spiral flange or ledge.

19. An underfeed furnace comprising a furnace chamber, a rotative firepot therein, means to conduct air to the firepot, a fixed upstanding centrally arranged spiral ledge extending upwardly through the firepot, means to deliver fuel to said chamber and spiral fuel feed arms rotative with the firepot to force the fuel toward said spiral ledge. 115 120

20. An underfeed furnace comprising a furnace chamber, a rotative firepot therein, means to conduct air to the firepot, a fixed upstanding centrally arranged spiral ledge extending upwardly through the firepot, means to deliver fuel to said chamber, spiral fuel feed arms rotative with the firepot to force the fuel upwardly toward said spiral 125 130

ledge, and a fixed ash scraper above the firepot to scrape the ashes outwardly away from the rotative firepot.

21. An underfeed furnace comprising a furnace chamber, a rotative firepot therein, an air conduit extending upwardly through the chamber and into the firepot with means for forcing air therethrough, said conduit being provided within the firepot with a fixed spiral flange or ledge, spiral fuel feed arms rotative in said chamber with the firepot, and means to deliver fuel to the chamber in the path of the said arms.

22. An underfeed furnace comprising a furnace chamber, a firepot therein, anti-friction bearings between said firepot and the fixed walls of the chamber, means for rotating said firepot, spiral fuel feed arms extending outwardly from the open lower end of the firepot over the floor of the furnace chamber, means to feed fuel into the chamber into the path of the said arms, a fixed upright centrally arranged spiral ledge within the rotative firepot, and means to force air into the fire bed.

23. An underfeed furnace comprising a furnace chamber, a rotative firepot therein, anti-friction bearings between said firepot and the fixed wall of said chamber, spiral fuel feed arms extending outwardly from the lower open end of the firepot over the floor of the furnace chamber, means to feed fuel into the chamber into the path of said arms, a fixed upright centrally disposed spiral ledge within the firepot, said firepot

being provided with an annular rack, and a pinion meshing with said rack, with means to rotate it.

24. An underfeed furnace comprising a furnace chamber, a rotative firepot therein, anti-friction bearings between said firepot and the fixed wall of said chamber, spiral fuel feed arms extending outwardly from the lower open end of the firepot over the floor of the furnace chamber, means to feed fuel into the chamber into the path of the said arms, a fixed upright centrally disposed spiral ledge within the firepot, said firepot being provided with an annular rack, a pinion meshing with said rack, means to rotate it, an air blower for delivering air to the firepot, and a motor for driving said fan and connected by a speed reducing train of gears to said pinion.

25. An underfeed furnace comprising a furnace chamber, a rotative firepot therein, a fixed upstanding air conduit provided within the firepot with exit openings and with a spiral ledge, spiral fuel feed arms rotative with the firepot, means to feed fuel to the chamber into the path of said arms, and means to scrape the ashes from the ash bed above the firepot.

Signed at Seattle, Wash., this 8th day of December, 1914.
